LEMON SECTIONIZER

John M. Ross, Upland, Frederick W. Riddington, Ontario, and Richard O. Spencer, South Laguna, Calif., assignors to Sunkist Growers, Inc., Sherman Oaks, Calif.

Filed Aug. 31, 1972, Ser. No. 285,178

Term of patent 14 years

Int. Cl. D15—08

U.S. Cl. D55—1 A

FIG. 4.

FIG. 1 is a perspective view of the lemon sectionizer showing our new design;

FIG. 2 is a front elevation view thereof;

FIG. 3 is a left-end elevational view of FIG. 1; and

FIG. 4 is a top plan view of FIG. 1.

We claim:

The ornamental design for a lemon sectionizer, as shown.
